US00D625005S

(12) **United States Design Patent**
Zimmer et al.

(10) **Patent No.:** **US D625,005 S**
(45) **Date of Patent:** **** Oct. 5, 2010**

(54) **BIOPSY SITE MARKER**

(75) Inventors: **Brian S. Zimmer**, Indianapolis, IN (US); **Zachary R. Nicoson**, Indianapolis, IN (US); **Laresha V. Fluker**, Indianapolis, IN (US)

(73) Assignee: **Hologic, Inc.**, Marlborough, MA (US)

(**) Term: **14 Years**

(21) Appl. No.: **29/343,900**

(22) Filed: **Sep. 21, 2009**

(51) **LOC (9) Cl.** **24-02**

(52) **U.S. Cl.** **D24/140**

(58) **Field of Classification Search** **D24/133, D24/134, 135, 136, 137, 138, 139, 140, 141, D24/142, 143, 146, 150, 152, 144, 145, 147, D24/148, 149, 151, 153, 154, 127, 128, 129, D24/130, 107–108, 112, 111, 200; D23/233, D23/235; D8/40, 47, 57, 60, 67, 68, 69, D8/80, 82, 83, 84, 93, 94, 97, 107, 72, 73, D8/74, 52, 56; 600/101, 104, 105, 106, 109, 600/112, 131, 135, 160, 162, 215, 431, 564, 600/568, 184, 220–223, 224, 225–227, 201–203, 600/210–218; 606/129, 186, 4, 5, 6, 7, 102, 606/86 A, 86 B, 119, 151, 157, 191–200; 81/9.22; 604/48**
